STOOL

Clair A. Samhammer, Orange, Calif., assignor to Samsonite Corporation, Denver, Colo.

Filed Jan. 12, 1973, Ser. No. 323,053

Term of patent 14 years

Int. Cl. D6—01

U.S. Cl. D6—35

FIG. 1.

FIG. 2.

FIG. 3.

FIG. 1 is a perspective view of a stool, showing my new design;

FIG. 2 is a side elevational view; and

FIG. 3 is a bottom plan view.

The side opposite that shown in FIG. 2 has the appearance of that shown in FIG. 2.

I claim:

An ornamental design for a stool, as shown.
